(57) **CLAIM**

The ornamental design for a multimedia communications device, as shown.

DESCRIPTION

FIG. 1 is a front perspective view of a multimedia communications device showing the new design.

FIG. 2 is a rear perspective view of the multimedia communications device.

FIG. 3 is a left side perspective view of the multimedia communications device.

FIG. 4 is a right side perspective view of the multimedia communications device.

FIG. 5 is a top side perspective view of the multimedia communications device; and,

FIG. 6 is a top side perspective view of the multimedia communications device with a handset in an alternative position showing the bottom side of the handset.
